DESIGN FOR A BATTERY BOX

Walter Joy, Belmont, Mass., assignor to Hood
Rubber Company, Inc., Watertown, Mass., a
corporation of Delaware

Application September 6, 1935, Serial No. 58,459

Term of patent 14 years

To all whom it may concern:

Be it known that I, Walter Joy, a citizen of the United States, residing at Belmont, in the county of Middlesex and Commonwealth of Massachusetts, have invented a new, original, and ornamental Design for a Battery Box, of which the following is a specification, reference being had to the accompanying drawing, forming a part thereof.

The drawing shows a perspective view of a battery box embodying my design.

The end of the box which is not visible in the drawing is identical in appearance with the end that is visible and the side that is not visible is identical in appearance with the side that is visible.

I claim:

The ornamental design for a battery box as shown and described.

WALTER JOY.
